DESIGN.

—o—
W. HAYES.

WATCH CASE.

No. 17,680.

Patented Sept. 6, 1887.

UNITED STATES PATENT OFFICE.

WILLIAM HAYES, OF NEWARK, NEW JERSEY.

DESIGN FOR A WATCH-CASE.

SPECIFICATION forming part of Design No. 17,680, dated September 6, 1887.

Application filed May 13, 1887. Serial No. 238,157. Term of patent 7 years.

To all whom it may concern:

Be it known that I, WILLIAM HAYES, of Newark, in the county of Essex and State of New Jersey, have originated and produced a 5 new Design for Ornamenting Watch-Cases, of which the following is a description.

The design for a watch-case consists of a roughened background or surface simulating the appearance of fibers irregularly scattered over the surface and raised therefrom, and raised ornaments isolated or separated from each other and irregularly scattered over the roughened background or surface.

The design also consists of star and crescent ornaments scattered irregularly over the surface of a watch-case.

The accompanying drawing clearly represents by photography a watch-case embodying the design.

20 The background or main surface A of the case is roughened, and simulates in appearance that which would be produced by fine and coarse fibers scattered irregularly over the surface of the case and raised therefrom. Upon 25 the surface of the case are raised ornaments

B C, those ornaments B consisting of star-shaped projections, and the ornaments C consisting of crescent-shaped projections. The ornaments which consist of the projecting portions B C are in relief above the general surface or background A, and are, as clearly shown, disposed without regularity thereon. 30

What I claim as a design, and desire to secure by Letters Patent, is—

1. The design for a watch-case, consisting 35 of a roughened background or surface, A, simulating the appearance of fibers irregularly scattered over the surface and raised therefrom, and raised ornaments B C, isolated or separated from each other and irregularly 40 scattered over the background A, substantially as herein shown and described.

2. The design for a watch-case, consisting of the star and crescent ornaments scattered irregularly over its surface, substantially as 45 herein shown and described.

WILLIAM HAYES.
